[57] CLAIM

The ornamental design for a vehicle tire, as shown and
described.

DESCRIPTION

FIG. 1 is a side elevation view of a vehicle tire showing
my new design it being understood that the opposite
side is a mirror image thereof;

FIG. 2 is a front elevation view thereof;

FIG. 3 is a perspective view thereof it being understood
that the tread pattern is repeated throughout the cir-
cumference of the tire; and

FIG. 4 is an enlarged fragmentary front elevation view
thereof.
